Primary Examiner — Michael C Stout*Assistant Examiner* — Eric Eldone Tormanen(74) *Attorney, Agent, or Firm* — McCoy Russell LLP(57) **CLAIM**

The ornamental design for a pedestal cart as shown and described.

DESCRIPTION

FIG. 1 is a top-front-right perspective view of a pedestal cart according to the claimed design.

FIG. 2 is a bottom-rear-right perspective view of the pedestal cart.

FIG. 3 is a front view of the pedestal cart.

FIG. 4 is a rear view of the pedestal cart.

FIG. 5 is a right side view of the pedestal cart.

FIG. 6 is a left side view of the pedestal cart.

FIG. 7 is a top view of the pedestal cart; and,

FIG. 8 is a bottom view of the pedestal cart.

The broken lines in the drawings illustrate portions of the pedestal cart that form no part of the claimed design.
